(57) **CLAIM**

The ornamental design for an induction range, as shown and described.

DESCRIPTION

FIG. 1 is a front perspective view of a first embodiment of an induction range, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of a portion of the induction range shown within the area designated as 8 in FIG. 1;

FIG. 9 is an enlarged view of a portion of the induction range shown within the area designated as 9 in FIG. 1;

FIG. 10 is a front perspective view of a second embodiment of the induction range, showing our new design;

FIG. 11 is a front view thereof;

FIG. 12 is a rear view thereof;

FIG. 13 is a left-side view thereof;

FIG. 14 is a right-side view thereof;

FIG. 15 is a top view thereof;

FIG. 16 is a bottom view thereof;

FIG. 17 is an enlarged view of a portion of the induction range shown within the area designated as 17 in FIG. 10;

FIG. 18 is an enlarged view of a portion of the induction range shown within the area designated as 18 in FIG. 10;

FIG. 19 is a front perspective view of a third embodiment of the induction range, showing our new design;

(Continued)

FIG. 20 is a front view thereof;
 FIG. 21 is a rear view thereof;
 FIG. 22 is a left-side view thereof;
 FIG. 23 is a right-side view thereof;
 FIG. 24 is a top view thereof;
 FIG. 25 is a bottom view thereof;
 FIG. 26 is an enlarged view of a portion of the induction range shown within the area designated as 26 in FIG. 19; and,
 FIG. 27 is an enlarged view of a portion of the induction range shown within the area designated as 27 in FIG. 19. The even-dash broken lines illustrating portions of the induction range form no part of the claimed design. The dot-dot-dash broken lines encircling enlargement portions of the induction range form no part of the claimed design. The contrast shown in grayscale in the figures represents a contrast of appearance.

1 Claim, 27 Drawing Sheets
